United States Patent Office

Des. 217,132

Patented Apr. 14, 1970

217,132

CREAMER

Ronald D. Argenta, Stafford Springs, Conn., assignor to Ready Food Products, Inc., Philadelphia, Pa., a corporation of Pennsylvania

Filed July 16, 1969, Ser. No. 18,223

Term of patent 14 years

Int. Cl. D9—04

U.S. Cl. D9—219

FIG. 1.

FIG. 3.

FIG. 5.

FIG. 1 is a side elevational view of a creamer showing my new design;

FIG. 2 is a top plan view thereof;

FIG. 3 is a rear elevational view of the creamer of FIG. 1;

FIG. 4 is a bottom view of the creamer of FIG. 1;

FIG. 5 is a sectional view of the creamer taken along line 5—5 of FIG. 4; and

FIG. 6 is an enlarged fragmentary section taken on line 6—6 of FIG. 5.

I claim:

The ornamental design for a creamer, as shown.
